UNITED STATES PATENT OFFICE.

LOUIS A. M. PHELAN, OF BELOIT, WISCONSIN, ASSIGNOR TO ABSOLUTE CON-TAC-TOR CORPORATION, OF BELOIT, WISCONSIN, A CORPORATION OF ILLINOIS.

THERMOSTATIC COIL.

Application filed September 22, 1924. Serial No. 739,005.

To all whom it may concern:

Be it known that I, LOUIS A. M. PHELAN, a citizen of the United States, residing at Beloit, in the county of Rock and State 5 of Wisconsin, have invented new and useful Improvements in Thermostatic Coils, of which the following is a full, clear, concise, and exact description, reference being had to the accompanying drawing, forming a 10 part of this specification.

My invention relates to thermostatic coils and more particularly to a device of this type wherein the bi-metallic strip is provided with an improved means for effecting an 15 increased efficiency in the expansion and contraction thereof.

It is commonly known that a considerable 20 part of the actuating force obtainable from bi-metallic strips is ordinarily wasted. Such strips comprise the controlling element in temperature control devices and are usually made of two metals fixed together, having different coefficients of expansion, and sometimes being formed in the shape of a spiral.

25 The purpose of such an arrangement is, of course, to use the spiral strip to turn or rotate a temperature control device in response to temperature changes in the bi-metallic strip. I find, however, that where the spiral strip 30 is in the form of a ribbon of considerable width, temperature changes will not only tend to rotate one end of the ribbon with respect to the other, but will also tend to curl each and every cross-sectional portion 35 of the ribbon. This cross-sectional curling of the strip will strengthen the strip against rotational effects, and thereby greatly diminish the effectiveness of the strip in controlling the temperature device.

40 An object of my invention is, therefore, to provide an improved design of bi-metallic strip having means for minimizing the bending

45 stresses in a crosswise direction, thereby increasing the rotational ability produced by expansion and contraction lengthwise, and permitting this lengthwise expansion and contraction to operate unhampered by any tendency of the bi-metallic strip to strengthen itself against such action by curling.

50 In the drawings wherein I have illustrated an embodiment of the preferred form of my invention:

Figure 1 is a top plan view of a bi-metallic strip embodying my invention:

Fig. 2 is a cross-sectional view of the 55 same;

Fig. 3 illustrates in cross section the manner in which a bi-metallic strip will curl when not embodying my invention;

Fig. 4 illustrates in cross section the manner in which a bi-metallic strip will curl when embodying my invention; and

Fig. 5 is a side elevational view of this strip formed in a spiral.

In the drawings the bi-metallic strip 5 of 65 the thermostatic coil is illustrated as comprising an inner metal 6 and an outer metal 7, the line of junction being shown at 8. The two metals are soldered or brazed together, so that the full effect of the different 70 expansions is obtained, there being no possible slipping of one metal on the other. I employ two metals, such as differ at least in expansibility and may be readily united by soldering or brazing. I prefer invar steel, 75 or the like, for the outer metal and brass, or its alloys as the inner metal, but other combinations may be made with success.

An important feature of the present invention is the form given to the outer metal 7 80 of the ribbon or strip forming the spiral coil, as shown in Fig. 5, being in two parts *a* and *b*. In other words, a longitudinal groove 9 is provided which preferably divides the outer metal 7 substantially in two equal 85 strips *a* and *b*. This form minimizes the bending stresses in the ribbon or strip 5 in a crosswise direction, so that they are practically negligible. Providing the central longitudinal groove 9 tends to localize any 90 curling tendency and restrict it to the edge portions of the ribbon or strip 5. I have, however, found this curling tendency practically unnoticeable and unable to strengthen the bi-metallic strip against rotational 95 effects.

When formed spirally, the bi-metallic strip 5 is usually quite wide. If so desired, more than one longitudinal groove 9 may be provided, but this is entirely dependent 100 upon the width of the strip. Moreover, the coil is made more sensitive with this groove which admirably serves as means for increasing the efficiency during expansion and contraction. When imparting the actuating force, a finer degree of sensitiveness or prompt response is noticeable, because the lengthwise expansion and contraction (which 105

are the rotational effects produced) are unhampered and free to act, without transverse bending stresses interfering.

It is believed that the principle underlying this invention, its functional law, and the merits and advantages which it possesses will be entirely clear to those skilled in the art without further detailed description of other equivalent specific forms in which the invention may obviously be embodied. Hence, without limiting the invention to the particular embodiment thereof herein selected for purposes of illustration and description;

15 I claim:

1. A bi-metallic element having at least one of its metals divided into a plurality of strips.
2. A thermostatic coil comprising metals of different coefficients of expansion and having at least one of said metals divided between its edges to minimize the bending stresses in a crosswise direction.
3. Means for increasing the rotational

effects of a spirally formed bi-metallic element comprising longitudinally spaced strips serving as one of the metals of said bi-metallic element.

4. Means for increasing the rotational effects of a spirally formed bi-metallic element comprising the provision of at least two strips serving as one of the metals, said strips being disposed along the edges of the other metal so as to localize the cross-sectional bending stresses adjacent the outer edge portions thereof.

5. A bi-metallic element of substantial width having its outer metal separated so as to reduce cross-sectional curling of said element.

6. A bi-metallic element of substantial width having at least one of its metals of such formation as to reduce cross-sectional curling of said element.

In witness whereof, I have hereunto subscribed my name.

LOUIS A. M. PHELAN.
